United States Patent Office.

JAMES HENRY CULVER, OF SAN FRANCISCO, CALIFORNIA, ASSIGNOR TO
HIMSELF AND CORNELIUS LEONARD.

Letters Patent No. 64,203, dated April 30, 1867.

IMPROVEMENT IN CALIPERS.

The Schedule referred to in these Letters Patent and making part of the same.

TO ALL WHOM IT MAY CONCERN:

Be it known that I, JAMES H. CULVER, of the city of San Francisco, San Francisco county, State of California, have invented certain new and useful Improvements in "Calipers;" and I do hereby declare the following description and accompanying drawings are sufficient to enable any person skilled in the art or science to which it most nearly appertains to make and use my said invention without further invention or experiment.

The nature of my invention is to provide an improvement in calipers by which the difficulties met with in obtaining the dimensions of anything, in which the calipers must be changed before they can be removed, are overcome.

To more fully explain my invention, reference is had to the accompanying drawings and letters marked thereon, of which—

Figure 1 represents a side elevation of a pair of calipers of my invention, showing their application.

Figure 2, an edge view showing the joint.

Figure 3 shows their application as inside calipers.

Similar letters indicate like parts in each of the figures.

A A are the arms, curved or straight, as most convenient, with a joint at D like ordinary calipers. The leg B is jointed at C, being fixed in position by the tightening-screw *a*. At the point *b*, on the inside, the leg or limb B makes a right angle, so that it will come in contact with the shoulder *c*, thus preventing B from passing a certain limit or point.

When the calipers are used to take an outside measurement, the shoulders *b* and *c* are brought together and the line B firmly fixed by the set-screw *a*. The calipers are then applied, as in fig. 1, and, after ascertaining the size, the screw *a* is loosened, thus allowing the limb to be turned back to remove the calipers. After removing them, the limb B is moved up as far as the shoulders *b* and *c* will allow and the set-screw *a* again tightened, thus securing it in the same place as before it was removed from the object measured. The same instrument may be used for measuring the inside diameter, as shown in fig. 3.

Having thus described my invention, what I claim, and desire to secure by Letters Patent, is—

A pair of calipers, either for inside or outside measuring, constructed with the joint C and shoulders *b* and *c*, substantially as and for the purpose set forth.

In witness whereof I have hereunto set my hand and seal.

JAMES H. CULVER. [L. S.]
